UNITED STATES PATENT OFFICE

LEO L. LEWIS, OF PLAINFIELD, NEW JERSEY, ASSIGNOR, BY MESNE ASSIGNMENTS, TO
AUDITORIUM VENTILATING CORPORATION, OF JERSEY CITY, NEW JERSEY, A COR-
PORATION OF NEW JERSEY

AIR DIFFUSER FOR AUDITORIUMS AND THE LIKE

Application filed June 21, 1927. Serial No. 200,365.

This invention relates to ventilating and air distributing systems, and particularly to outlets through which air may be discharged into and distributed in rooms. Heretofore it has been frequent practice to discharge conditioned air into the room through outlets or openings in the ceiling, and in order to distribute this ingoing air laterally or more or less in a horizontal direction beneath the ceiling, deflectors, rosettes, or pans have been suspended just below the ceiling in alignment with the discharge openings, so that all or a considerable portion of the air striking the distributing pans or devices will be deflected laterally.

Artists and architects have objected vigorously to the use of such deflectors or pans spaced below the ceiling, because of the fact that they destroyed the beauty of ceiling designs, cast shadows, and broke up the lines or spoiled the decorative scheme or artistic effect sought to be conveyed by a particular design. In some instances where head room is limited, the pans or deflectors suspended below the ceiling have interfered with or obstructed the line of sight.

An object of this invention is to provide an improved air distributing outlet useful for ventilating and air distributing systems, with which there will be no projections materially beyond the interior surface of the ceiling or walls of the room in which the outlets are located; which will not objectionably interfere with the artistic design of the ceiling or walls of a room; which will not cast shadows; which will effectively diffuse or distribute the discharged air laterally and along the wall through which the outlet opens; and which will not interfere with sight lines.

A further object of the invention is to provide an improved air distributing outlet, which may be disposed entirely outside of a room; which will effectively distribute or diffuse the air discharged thereby laterally in one or a plurality of directions; which will be inconspicuous in appearance; and which may be constructed to conform to artistic designs one may desire to place upon the wall of the room through which the outlet opens.

A further object is to provide an improved

air distributing device or an outlet for air conduits, by which air may be deflected laterally at relatively small acute angles to the lateral wall of the conduit through which the air is discharged.

A further object is to generally improve and simplify air distribution outlets and devices, and provide an improved air distribution outlet or system which will be relatively simple, effective, and inexpensive.

Various other objects and advantages will be apparent from the following description of an embodiment of the invention, and the novel features will be particularly pointed out hereinafter in connection with the appended claims.

In the accompanying drawings:—

Fig. 1 is a sectional elevation through a portion of the ceiling and roof of a theatre or auditorium having ventilating and air distributing outlets opening through the ceiling in accordance with this invention.

Fig. 2 is a sectional elevation, on a somewhat larger scale, of one of the distributing air ducts.

Fig. 3 is a sectional plan of the bottom part of such a duct, and showing in greater detail the discharge tubes or nozzles; and

Fig. 4 is a sectional elevation, on a somewhat larger scale, of the bottom part of a distributing duct and showing one example of a mounting for the discharge tubes or nozzles.

In the illustrated embodiment of the invention, the room 1 to be ventilated or supplied with air may have a ceiling 2 of any suitable or desired form or construction, the ceiling in the particular example selected having a dome portion 3 arising from a central portion of the ceiling. This dome portion may be of circular, elliptical, polyhedral or of any other desired shape, and around the base of the dome a discharge or distributing air duct or conduit 4 may be provided conforming to the shape of the rim of the dome. This duct or conduit 4 may be located at the junction between the dome base and the horizontal part of the ceiling, and may be connected, at one or more points, to a main air supply conduit 5, such as through branch or spider leg drop conduits 6. This duct or

conduit may also take the form of a straight or curved line, or lines following some well-established feature of the decoration, such as a beam or line of offset in the ceiling. These branch conduits 6 may be provided with individual controlling dampers 7, and partitions provided in the duct 4 between the branches, so that the air supplied to the distributing conduit 4 may be received in the latter at one or a plurality of points, and the discharge from different portions of the conduit controlled, as may be desired. As a matter of convenience, the distributing duct 4 may be built around a channel beam 8 forming a part of the ceiling construction at the dome, although the channel beam is an un-essential feature, and in no way materially affects or modifies the action of the outlet.

Along the bottom or other desired lateral wall of the conduit, a plurality of discharge passages, nozzles or tubes 9 may be arranged, and these discharge nozzles or tubes open outwardly through the ceiling 2, with their lower or discharge ends substantially flush with the interior or room surface of the ceiling. These tubes are oblique to the room surface of the ceiling and preferably arranged at a relatively small acute angle to said surface, such as less than forty-five degrees, so as to discharge air in a plurality of directions as closely as possible parallel to the ceiling or other wall through which the outlet opens or discharges air. Some of the tubes or passages may be arranged to discharge obliquely into the room at one side of the axis of the distributing conduit, and others to discharge into the room at an approximately opposite direction with respect to the axis of the distributing conduit. For example, the tubes may be arranged in such a manner that alternate tubes will discharge in the same direction, with adjacent tubes pointing obliquely in approximately opposite directions as shown clearly in the drawing. These tubes have considerable length and project well into the interior of the conduit in directions transverse to the longitudinal axis of the distributing conduit, that is, transversely of the direction of air flow in the distributing conduit.

The tubes are preferably substantially straight or given lengths sufficient to cause the air passing through the same to be given substantially the same direction as the axis of that tube. The lengths of the tubes, for example, may be materially greater than the minimum cross sectional dimension of the tube, so that the air passing through the tube will remain therein long enough to be given a direction of travel which will be parallel to the axis of the tube instead of being given merely an eddy flow or partial deflection. The tubes may be stacked, one upon the top of the other, to whatever height may be desirable, or one or more partitions 9^a may be

placed in a single tube to give the proportions or ratio of length to depth which are necessary to control the deflection of air.

By properly arranging the discharge tubes or nozzles at the desired inclination to the ceiling, the wideness of distribution or diffusion of the air discharged thereby may be accurately determined or controlled. The nozzles or tubes are in effect branch passages leading from the distributing conduit to a room, but are located practically wholly within the conduit.

The air discharge tubes or nozzles may be in that wall of their conduit which faces the room to which they lead, and while preferably the distributing conduit having the tubes or nozzles is located entirely outside of but adjacent the room, it will be understood that in some instances the conduit may run more or less within the room very much as a beam, the purpose of the tubes or nozzles being to distribute the discharged air in such a manner that diffusion of that air with the air of the room will take place before striking occupants of the room and subjecting them to direct drafts.

The inner end of each tube 9 is preferably oblique to the axis of the tube and opens upwardly to facilitate the entrance of air thereto and to reduce to a minimum the eddy currents produced by the change in direction of the air entering the tube from the distributing conduit and the plane of the outer end of the tube is parallel with and substantially flush with the plane of the wall through which it opens. The tubes 9 may be used without grille coverings for their discharge ends, and the most efficient results are obtained without obstructions to the open ends of the tubes. However, it has been found that excellent results may also be obtained when the discharge openings of the tubes are concealed or covered by grille work, which may have a decorative design.

In Fig. 4, one example of the use of decorative grille work is illustrated, in which the tubes 9 are secured in a suitably reinforced ceiling or wall 2, and a grille plate 10 may be secured to the under face of this ceiling wall in any suitable manner, so as to cover the discharge openings of the tubes 9. Any desired mounting of the tubes 9 in the ceiling 2, however, may be employed, instead of that illustrated.

In the preferred construction, the air is conveyed through the main duct 5 at a fairly high velocity, the velocity being reduced in the drop passages 6, and still further reduced in the distributing duct or conduit 4. It will be observed that the entire outlet, and the supply and distributing conduits may be and preferably are disposed exteriorly of the room, and that the outlets open into a room in an inconspicuous manner, and in such a manner that the openings may be effectively

concealed by decorative grille work and without interfering with the artistic design or construction of the walls of the room through which the outlets discharge air.

5 It will be understood that various changes in the details, which have been herein described and illustrated in order to explain the nature of the invention, may be made by those skilled in the art within the principle and scope of the invention as expressed in the appended claims:

10 1. In a ventilating or air distributing system for a room and in combination, an air supply conduit running adjacent and approximately parallel to a wall of said room and having air discharge passages opening into said room through a lateral wall of said conduit and substantially flush with the room surface of said wall, each of said passages extending obliquely to said surface and at their inner ends opening into said conduit in directions transverse to the direction of travel of the air along the conduit.

15 2. In a ventilating or air distributing system for a room and in combination, an air supply conduit running adjacent and approximately parallel to a wall of said room and having air discharge passages opening into said room through a lateral wall of said conduit and substantially flush with the room surface of said wall, each of said passages extending obliquely to said surface and at their inner ends opening into said conduit in directions transverse to the direction of travel of the air along the conduit, some of said passages discharging air in one direction into said room, and others discharging air in approximately the opposite direction in said room.

20 3. In a ventilating or air distributing system for a room and in combination, an air supply conduit running adjacent and approximately parallel to a wall of said room and outside of said room, and discharge tubes projecting into said conduit from a lateral wall thereof and arranged with their outer discharge ends substantially flush with the room surface of the wall, and opening into said conduit in directions transverse to the direction of travel in said conduit.

25 4. In a ventilating or air distributing system for a room and in combination, an air supply conduit running adjacent and approximately parallel to a wall of said room and outside of said room, and discharge tubes projecting into said conduit from a lateral wall thereof and arranged with their outer discharge ends substantially flush with the room surface of the wall, said tubes projecting into said conduit at an inclination to said wall surface and in a direction transverse to the direction of air flow in said conduit.

30 5. In a ventilating or air distributing system for a room and in combination, an air supply conduit running adjacent and ap-

proximately parallel to a wall of said room and outside of said room, and discharge tubes arranged in said conduit and discharging through a lateral wall thereof substantially flush with the room surface of the wall, said tubes being substantially straight and extending into said conduit in a plurality of directions transverse to the direction of air flow in said conduit.

35 6. In a ventilating or air distributing system for a room and in combination, an air supply conduit running adjacent and approximately parallel to a wall of said room and outside of said room, and discharge tubes projecting into said conduit from a lateral wall thereof and discharging through said wall substantially flush with and obliquely to the room surface of the wall, said tubes being substantially straight and projecting into said conduit in directions transverse to the direction of air flow in said conduit.

40 7. In a ventilating or air distributing system for a room having a ceiling, and in combination an air supply conduit running above but approximately parallel to said ceiling, and having air discharge passages opening downwardly through and obliquely to said ceiling, the lower ends of said passages being substantially flush with the room surface of said ceiling, each passage being substantially straight and extending transversely of the direction of air flow in said conduit.

45 8. In a ventilating or air distributing system for a room and in combination, an air supply conduit running adjacent and approximately parallel to a wall of said room and having air discharge passages opening into said room through a lateral wall of said conduit and substantially flush with the room surface of said wall, each of said passages extending obliquely to said surface and at their inner ends opening into said conduit in directions transverse to the direction of travel of the air along the conduit, the inner ends of said passages being oblique to their axes and opening towards the lateral wall of the conduit opposite that through which the passages discharge.

50 9. An air distributing device comprising a conduit, a plurality of tubes extending into said conduit from a lateral wall of said conduit, at a relatively small acute angle to said lateral wall, and in directions transverse to the axis of said conduit.

55 10. An air distributing device comprising a conduit, and a plurality of tubes extending through a lateral wall of said conduit and opening at their inner ends into said conduit in directions transverse to the longitudinal axis of said conduit, said tubes discharging from said conduit alternately at opposite inclinations to said lateral wall of said conduit.

60 11. An air distributing device comprising

- a conduit, and a plurality of tubes extending through a lateral wall of said conduit and opening at their inner ends into said conduit in directions transverse to the longitudinal axis of said conduit, said tubes discharging from said conduit alternately at opposite inclinations to said lateral wall of said conduit and having their outer discharge ends substantially flush with said lateral wall.
- 10 12. An air distributing device comprising a conduit, and a plurality of tubes extending through a lateral wall of said conduit and opening at their inner ends into said conduit in directions transverse to the longitudinal axis of said conduit, said tubes discharging from said conduit in directions making acute angles less than 45° to said lateral wall.

- 15 13. An air distributing device comprising a conduit, and a plurality of tubes extending through a lateral wall of said conduit and opening at their inner ends into said conduit in directions transverse to the longitudinal axis of said conduit, said tubes discharging from said conduit in directions making acute angles less than 45° to said lateral wall, some tubes discharging towards one side of said conduit and others towards the opposite side.

- 20 14. An air distributing device comprising a conduit, and air discharge tubes arranged in said conduit transversely to the longitudinal axis of said conduit and at an acute angle of less than 50° to a lateral wall of the conduit, the inner and inlet ends of the tubes opening into said conduit and the outer and discharge ends being substantially flush with said wall.
